(57) **CLAIM**

The ornamental design for a mobile scaffold skid bar, as shown and described.

DESCRIPTION

FIG. 1 is a perspective view of a mobile scaffold skid bar showing my new design. The broken lines are for illustrative purposes only and form no part of the claimed design.

FIG. 2 is a perspective view thereof;

FIG. 3 is a front view thereof;

FIG. 4 is a top plan view thereof;

FIG. 5 is a bottom plan view thereof;

FIG. 6 is a rear elevation view thereof; and,

FIG. 7 is an end elevation view thereof, the opposite end being a mirror image thereto.
